(57) CLAIM

The ornamental design for a sneaker cotton slipper, as shown and described.

DESCRIPTION

FIG. 1 is a perspective view of a sneaker cotton slipper showing my new design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

Broken lines in the drawings depict stitching lines and form part of the claimed design, except for the broken lines representing the shoelaces; the broken lines which representing the shoelaces form no part of the claimed design.

1 Claim, 7 Drawing Sheets
